US00D629760S

(12) **United States Design Patent**
Lindsey et al.

(10) **Patent No.:** US D629,760 S
(45) **Date of Patent:** ** Dec. 28, 2010

(54) **INTERFACE ON AN ELECTRONICS CONNECTOR**

(75) Inventors: **Scott E. Lindsey**, Brentwood, CA (US);
Jovan Jovanovic, Santa Clara, CA (US);
David S. Hendrickson, Los Gatos, CA (US)

(73) Assignee: **AEHR Test Systems**, Fremont, CA (US)

(**) Term: **14 Years**

(21) Appl. No.: **29/327,293**

(22) Filed: **Nov. 3, 2008**

(51) **LOC (9) Cl.** 13-03

(52) **U.S. Cl.** D13/154

(58) **Field of Classification Search** D13/147,
D13/154, 184; 439/500, 607-610, 883, 892,
439/894, 901, 943

See application file for complete search history.

(57) **CLAIM**

The ornamental design for an interface on an electronics connector, as shown and described.

DESCRIPTION

The sole FIGURE is a top plan view of an interface on an electronics connector showing our new design.

The broken line portion of the FIGURE drawing is included to show unclaimed subject matter only and forms no part of the claimed design.

1 Claim, 1 Drawing Sheet
